ELEVATOR CONTROL SYSTEM

William F. Eames, Westfield, N. J., assignor
to Westinghouse Electric Elevator Company,
Jersey City, N. J., a corporation of Illinois

Application August 19, 1941, Serial No. 407,414

14 Claims. (Cl. 172—152)

My invention relates to elevator control systems and, more particularly, to means for stopping the cars level with the floors and releveling them if necessary while they are making stops at the floors.

One object of the invention is to provide a low-price system which will give quick and accurate leveling action in stopping a car at a floor and which will also provide rapid and effective releveling of a car when releveling is necessary.

Another object is to provide a leveling and releveling system which will require the use of less complicated floor selectors and circuits than those heretofore found necessary for use in leveling and releveling systems.

A further object is to provide a system which will automatically cause an elevator car, in making a one-floor run, to accelerate to its most desirable speed, then decelerate at its most desirable rate for a one-floor run when the car switch is moved to its "on" position and then promptly returned to its center or "off" position.

A still further object is to provide a system in which compensation may be made for temperature changes which affect the leveling action.

It is also an object to so control the energization of the generators embodied in variable voltage elevator systems as to secure the most desirable deceleration of the elevator cars when making stops at their floor levels.

Other objects will become apparent from the following description of the invention taken in conjunction with the accompanying drawings, in which:

Figure 1 is a diagrammatic representation in what is known as the straight-line style of control system for an elevator car embodying my invention;

Fig. 1A is an explanatory illustration of the relays embodied in the control system of Fig. 1—the illustration shows the relays with their coils and contact members disposed in horizontal alignment with their positions in straight-line circuits of Fig. 1, so that the identification of any relay and the position of its coil and contact members in the straight-line circuits may be readily determined;

Fig. 2 is a diagrammatic representation of an inductor relay to be mounted on a car and a pair of inductor plates therefor mounted upon the walls of the hatchway in which the car operates as looking from the hatchway wall toward the car; and

Fig. 3 is a reduced view in side elevation of the inductor relay shown in Fig. 2.

The relays embodied in the system are designated as follows:

U	=up direction switch
D	=down direction switch
UR	=up direction relay or control device
DR	=down direction relay or control device
M	=car running relay
N	=auxiliary car running relay
GR	=high speed start relay
1P	=low speed decelerating relay
2P	=intermediate speed decelerating relay
3P	=high speed decelerating relay
L	=leveling inductor relay
LU	=up leveling relay
LD	=down leveling relay
TA	=time delay relay for one-floor runs
TB	=anti-plugging relay
TC	=smooth-start relay
Q	=counter-electromotive force relay
K	=door-operating relay.

Referring more particularly to the drawings, I have illustrated a car C for serving a plurality of landing floors as suspended by a suitable cable 25 which passes over a hoisting drum 12 to a suitable counterweight 13. A hoisting motor H is provided for operating the hoisting drum by means of a shaft 14 to raise and lower the car. The hoisting motor H is provided with a field winding HF which is connected for constant energization to a pair of supply conductors L+ and L-, which may be connected to a supply of electrical energy by a pair of line switches 15 and 16.

35 A variable voltage system of control is provided for controlling the operation of the hoisting motor H, wherein the hoisting motor armature HA is connected in a closed circuit 21 with the armature GA of a generator G. The generator 40 is provided with a separately excited field winding GF which is connected for energization in a loop circuit 22 with the armature RA of a regulator R, so that the output of the generator and, consequently, the speed and direction of operation of the hoisting motor H may be controlled by controlling the operation of the regulator. An adjustable resistor r1 is connected in the circuit 45 of the generator field winding for adjusting the resistance of that circuit to any desired value. A pair 50 of commutator pole winding 24 for the generator G is connected in series in the loop circuit 21. The armatures of the generator and the regulator may be mounted on a common shaft 20 for operation by any suitable constant speed motor 55 (not shown).

The regulator R is provided with a self-exciting field winding RCF, a pattern field winding RPF, a differential field winding RDF, and a series field winding RSF.

The self-exciting field winding RCF is connected in the loop circuit 22 in series with the regulator armature RA and the generator field winding GF. The total resistance of this circuit should be made equal to the volts that the regulator will produce when one ampere flows through its self-exciting field winding. It has been found that with this adjustment perfect regulation will be obtained with no hunting effects.

The pattern field winding RPF is disposed to be connected across the supply conductors L+ and L-, so that the generator voltage and the direction of operation may be controlled by controlling the direction and the value of the current in the pattern field. For a given excitation of the pattern field, the regulator will produce a voltage which will excite the generator field winding GF. As soon as current starts to flow through the generator field winding circuit, the self-exciting field winding RCF excites the regulator to force the current through the generator field winding.

A plurality of resistors r6 to r10 are connected in the circuit of the pattern field winding to so control the value of that winding that the generator G will be energized to cause the car to accelerate, run and decelerate at predetermined desired speeds.

The differential field winding RDF is connected across the terminals of the generator armature GA. An adjustable resistor r3 is inserted in series with the differential field winding RDF, so that the value of the differential field winding may be adjusted as desired. This differential field winding and the pattern field winding RPF are adjusted to produce the same and opposite voltage in the regulator for a given excitation of the pattern field.

The regulator series field RSF is connected in series in the loop circuit 21 between the armatures of the generator and the hoisting motor. This field winding is provided to cause the regulator to give the generator field winding sufficient excitation to compensate for the IR drop in the hoisting motor. The regulator R is disclosed and claimed in Danilo Santini Patent No. 2,221,610, granted November 12, 1940, and assigned to Westinghouse Electric Elevator Company. Further details regarding the regulator and its functions, if desired, may be secured in the patent.

An electromagnetic brake 19 having a coil 19a is associated with the shaft 14 for stopping and holding the car when the power to the hoisting motor is cut off. A pair of resistors r4 and r5 are disposed in the circuit of the coil 19a to cause a quick brake action under certain conditions hereinafter defined.

A car switch CS is mounted in the car for use by the car attendant to start and stop the car. The car may be started in the up direction by moving the car switch counter-clockwise and in the down direction by moving it clockwise. When the car switch is centered, it causes the car to stop at the next floor.

The car switch controls the car by controlling the up direction relay UR and the down direction relay DR, which, in turn, control the up direction switch U and the down direction switch D.

The up direction switch U and the down direction switch D control the energization of the generator G by connecting the pattern field winding of the regulator to the supply conductors L+ and L- for up direction or down direction operation.

The car running relay M is controlled by the direction switches U and D, and is provided for controlling the brake 19 and preparing certain circuits for operation when the car switch is thrown for movement of the car.

The auxiliary car running relay N is controlled by the relay M, and is provided for further preparing the control system for operation after the action of the car running relay M.

The high-speed starting relay GR is controlled by the direction switches U and D, and is provided for short-circuiting the decelerating resistors in the pattern circuit of the regulator when the car is being started.

The smooth-start relay TC is a time delay relay controlled by the auxiliary car running relay N for controlling the operation of the starting relay GR to secure smooth starting operation of the car, by preventing application of full speed until the car has gotten started at low speed. The relay TC should have a time delay of approximately .3 second in opening after it is de-energized.

The door relay K is provided for controlling the door operating motor (not shown) to cause it to open the doors at a floor when the car makes a stop thereat, and to prevent it from opening the doors while the car is running or is conditioned to start.

The counter-electromotive force relay Q is connected across the loop circuit 21 to prevent operation of the door relay K to open any door while the hoisting motor is operating above a predetermined low speed.

Any suitable landing system for causing the car to stop level with the floor after the car switch is centered for a stop may be employed. However, I have illustrated as one suitable system the automatic inductor relay system described and claimed in the copending application of Danilo Santini, filed Sept. 4, 1941, Serial No. 409,491, and assigned to the Westinghouse Electric Elevator Company. This landing system includes the inductor relay L which may be mounted on top of the elevator car C in position to come adjacent to an up inductor plate E and a down inductor plate F mounted on the walls of the hatchway (not shown) at each floor landing by means of a plurality of angle braces 28. In this particular illustration it will be assumed that the inductor plates E and F are each about 21 inches long and that the inductor relay is about 7 inches long. The plates should be so mounted in vertical, overlapping position in the hatchway, and the inductor relay L should be so mounted on the car that the relay will pass between the plates and close to them without touching them as the car moves up and down in the hatchway. Furthermore, the relative position of the relay and the plates should be such that if the car floor is level with floor landing at which the car is stopped, the center of the relay, as indicated by the line x-x will be midway between the upper end of the inductor plate F and the lower end of the inductor plate E, as shown in Fig. 2.

The inductor relay is provided with two pairs of contacts 2UL and 1DL on its upper end and with two pairs of contacts 1UL and 2DL on its lower end. An armature 32 is provided for each

pair of contacts. The armatures for operating the contacts 2UL and 1UL should be disposed in position to be operated by the inductor plate E and the armatures for operating the contacts 2DL and 1DL should be disposed in position to be operated by the inductor plate F when the coil of the relay is energized and the car moves the relay into position adjacent the inductor plates.

Although the drawings illustrate the plates E and F for only one floor landing, it is to be understood that a set of these plates is mounted at each floor served by the car and that they will be effective to stop the car only when the coil of the inductor relay L is energized to cause the car to stop.

The inductor contacts are normally closed and when the car comes down to a stop at the floor level the contacts open in the following order: 1UL, 2UL, 2DL and 1DL. When the car comes to a stop at the floor level, the contacts open in the following order: 1DL, 2DL, 2UL and 1UL. These actions deenergize the speed relays in the order 3P, 2P, 1P and the appropriate direction switch regardless of the direction of travel.

The high speed decelerating relay 3P controls the decelerating resistance r_2 included in the circuit of the regulator series field winding RSF, the resistance r_3 in the regulator differential field winding RDF, and the resistor r_8 in the circuit of the regulator pattern field winding RPF to cause the car to decelerate from high speed to intermediate speed.

The intermediate speed decelerating relay 2P controls the resistance r_9 in the regulator pattern field winding RPF and also conditions the circuits for switches U and D, and relays M and N.

The low speed decelerating relay 1P controls the resistance r_{10} in the circuit of the regulator pattern field winding RPF and the use of resistances r_4 and r_5 in the circuit of the brake coil 19a.

The time delay TA has a time delay of approximately 1.8 seconds when opening and is designed to provide a holding circuit for the up direction relay UR or the down direction relay DR when the car switch is thrown to its starting position and immediately returned to its center position for a one-floor run. This time delay relay holds the up or the down direction relay UR or DR energized for the amount of time necessary to cause the car to make a one-floor run. Under this predetermined set-up, the car will accelerate to and run at its high speed for a one-floor run and then decelerate at the proper time to a stop at the next floor.

The up leveling relay LU and the down leveling relay LD are controlled by the up contacts 1UL and the down contacts 1DL on the inductor relay L to cause the car to relevel if it rises above or sinks below the floor level at the landing at which it is stopped. If the car moves up for, say, $\frac{1}{2}$ inch the contacts 1DL will pass beyond the upper end of the plate F and will thereby be operated to cause the down direction switch D to move the car down to its floor level. On the other hand, if the car moves down, say, $\frac{1}{2}$ inch below the floor, the contacts 1UL will be operated by passing beyond the lower end of the plate E to operate the up direction switch 4 to cause the car to return upward to its floor level. Obviously, when the car returns to its correct level position it will so position the inductor relay L that all its contacts will be within the limits of the conductor plates E and F, and none of them will then operate to control the car.

The anti-plugging relay TB is provided with a time delay of approximately .3 second and operates to prevent energization of the inductor relay L when the car is traveling at full speed and for a fraction of a second after retardation starts so that the releveling switches cannot "plug" the hoisting motor at too high a speed.

The relay 3P is also provided with contacts 3P4 in the circuit of the up direction relay UR and DR which permits the release of the one floor run holding circuit provided by the relay TA when the car is closer to a floor than its normal one-floor run distance when it is started toward that floor.

It is believed that the invention will be best understood by the following assumed operation of the system illustrated in the drawings. It should be noted, however, that the particular dimensions, periods of delay, amounts of resistance involved, etc., are given as an illustration of what may be included in an operating system but that other values may be readily used in adapting the system to meet various operating conditions.

It will be assumed that the switches 15 and 16 are closed to prepare the control circuit for operation. This action energizes the hoisting motor field winding HF, the inductor relay L, the one-floor run relay TA and the smooth start relay TC. It will be assumed that the car is starting at the eighth floor landing level with the floor. Therefore, the inductor contacts 1UL, 2UL, 1DL and 2DL are all open because of the energized condition of the inductor relay L and its position between the inductor plates E and F for that floor (see Fig. 2).

It will be assumed now that the car attendant, desirous of making a one-floor run, closes the car switch CS in anti-clockwise direction to move the car down to the next floor. Inasmuch as this is to be a one-floor run, the attendant will close the switch only temporarily and then return it to its off position. The length of time the switch stays closed is not critical, but it must be centered before the car runs more than one-half the distance between floors. The temporary operation of the car switch for the down direction engages the contact 33 thereby energizing the down direction relay DR by the circuit

L+, UR3, DR, 33, L-

The energized down direction relay DR opens its back contacts DR1 and DR3 and closes its front contacts DR2, DR4, DR5 and DR6. The closing of the contacts DR6 energizes the door relay K to cause the door motor (not shown) to close the car gate and the floor landing door (not shown). The closing of the contacts DR2 prepares the circuit of the down direction switch D for operation. The closing of the contacts DR4 prepares the starting relay GR for operation. The closing of the contacts DR5 energizes the anti-plugging relay TB.

The energized anti-plugging relay TB opens its back contacts TB3 thus deenergizing the inductor relay L which causes the decelerating and leveling contacts 1UL, 2UL, 1DL, 2DL on the inductor relay to reclose, thus energizing the decelerating relays 1P and 2P and the leveling relays LU and LD which will remain in that condition until the next stop is to be made. This operation of the decelerating relays short circuits the decelerating resistors in the pattern field circuit to condition the decelerating means for action when the car is to be stopped.

It will be assumed now that the door motor has closed the car gate and the landing floor door thereby operating a limit switch (not shown) to stop the door motor and also closing the car gate and door safety contacts 40 and 41.

The closing of the contacts 40 and 41 completes the circuit for energizing the down direction switch D through

L+, D, US, DR2, 40, 41, UR2, L-

The energized down direction switch D closes its front contacts D1, D2, D4, D5, D6 and D8 and opens its back contacts D3, D7 and D9. The closing of contacts D5 completes a self-holding circuit for the down direction switch D. The closing of the contacts D4 energizes the car running relay M by the circuit

L+, M, D4, DR2, 40, 41, UR2

The closing of the contacts D1 and D2 prepares the pattern field winding RPF for operation in the down direction.

The closing of the contact members D9 energizes the decelerating relay 3P by the circuit

L+, LU3, D9, 3P, L-

The relay 3P opens its contacts 3P2 around the resistor r3; opens its contacts 3P1 to insert the resistor r2 in series with the regulator field winding RPF, and closes its contacts 3P3 to short circuit the resistor r8 in the pattern circuit. These connections are prepared to secure certain desired operations during deceleration of the car as will be described later when the car is decelerated to a stop at the next floor.

Returning now to the energized car running relay M, that relay opens its back contacts M1 and closes its front contacts M2, M3 and M4. The opening of the contacts M1 inserts the resistor r3 in series with the regulator differential field winding RDF for a purpose to be described later. The closing of the contacts M2 prepares the brake coil 19a for operation. The closing of the contacts M3 completes the circuit through the pattern field winding RPF for the down direction as follows:

L+, D2, RPF, D1, M3, r6, r7, TC1, L-

Inasmuch as the regulator commutator RA is being operated at a constant speed, this energization of the pattern field will cause the regulator to start the delivery of energy to the generator field winding GF as soon as the contacts N1 are closed.

The closing of the contacts M4 energizes the auxiliary running relay N by the circuit

L+, N, M4, D4, DR2, 40, 41, UR2, L-

The energized relay N closes its front contacts N1 and N2 and opens its back contacts N3 and N4. The closing of the contacts N1 energizes the generator field winding GF by the circuit

RA, RCF, r1, GF, N1

The generator now starts to deliver energy to the hoisting motor for operating the car downwardly. At the same time, the relay N closes its contacts N2 thereby energizing the brake coil 19a by the circuit

L+, N2, BK, 19a, M2, L-

The energization of the coil 19a releases the 70 brake 19 and the car starts to move downwardly.

The opening of the contacts N1 deenergizes the smooth start relay TC and after the expiration of .3 second that relay opens its contacts TC1 which had included the resistors r6 and r7 in the circuit 75

of the pattern field for starting purposes in order to secure a smooth start. The deenergization of the relay TC also closes its back contacts TC2 which thereupon complete the energization of the starting relay GR by the circuit

L+, GR, 40, 41, TC2, DR4, L-

The energized relay GR closes its contacts GR1 thereby short circuiting the resistors r7, r8, r9 and r10 in the pattern field winding RPF. This increases the energization of the pattern field circuit which causes the generator G to increase the speed of the hoisting motor H to its high running speed.

15 The car is moving downwardly now but it will be recalled that the one floor run relay TA was deenergized by the opening of the contacts N3 when relay N was energized. The relay PA will now, at the expiration of 1.8 seconds, when the 20 car is about half way between the floors, operate to open its contacts TA1 which were holding the down direction relay energized. It will be recalled that the car switch was closed only temporarily and that, therefore, the only circuit for the 25 down direction relay DR passed through the contacts TA1. Therefore, the present opening of these contacts deenergizes the down relay DR which thereupon closes its back contacts DR1 and DR3 and opens its front contacts DR2, DR4, DR5 and DR6.

The opening of the contacts DR4 deenergizes the starting relay GR which thereupon opens its contact members GR1 to eliminate the short circuit around the resistors r8, r7, r8, r9 and r10. 35 However, it will be observed by the drawings that inasmuch as the decelerating relays 1P, 2P, and 3P are energized, the resistors r8, r9 and r10 now stand short circuited by the decelerating contacts, but that the resistors r6 and r7 are completely included in the pattern field circuit. The effect of the resistors r6 and r7 is to reduce the speed of the car as it approaches the first point at which the inductor relay L starts decelerating the car. This point will be the upper end of the 40 plate E and will correspond to a position of the car approximately 21 inches from the next floor.

The opening of the contacts DR5 deenergizes the anti-plugging relay TB which, after the expiration of a .3 second delay, closes its back contacts TB3 thereby re-energizing the inductor relay L so that as it is brought opposite to and moved along the inductor plates E and F, its contacts will be operated sequentially to decelerate the car to a down stop at the seventh floor.

45 As the car approaches to the point approximately 21 inches from the floor landing, the inductor relay L approaches the inductor plate E, and as the contacts 1UL come exactly opposite the upper end of the plate E, they are operated 50 by the flux induced in the plate through the energized relay, to move to their open position, thus deenergizing the leveling relay LU to open its front contacts LU1 and LU3 and close its back contacts LU2. The opening of the contacts LU3 deenergizes the high speed decelerating relay 3P which thereupon opens its contacts 3P3 thus inserting the resistor r8 in the circuit for the pattern field winding to decelerate the car from its 55 high decelerating speed to its intermediate decelerating speed.

At the same time, the deenergized relay 3P recloses its contacts 3Pa, to short circuit a portion of the resistor r3 in series with the differential field winding RDF thereby strengthening that regulator field winding for the purpose of render-

ing the deceleration more effective. This action may be described as producing a tendency to hunt in the regulator but the action is directed oppositely to the car's movement so that the car retards at a higher rate than normal. It would ultimately reverse its direction of travel except the brake applies quickly when the car reaches floor level, which holds the car at floor level and prevents reversal.

Also at the same time the deenergized relay **3P** recloses its back contacts **3P1** and short circuits a portion of the resistor **r2** in circuit with the series field winding **RSF** to strengthen that series field winding to keep the regulation flat.

As the car decelerates from its high decelerating speed to its intermediate speed, it approaches to within approximately 14 inches of the down stop at the seventh floor and thereby moves the energized inductor relay **L** down to such a point that its contacts **2UL** come opposite the upper edge of the plate **E** and are operated to open position by the induced flux passing through the plate and the armature attached to the contacts. The opening of the contacts **2UL** deenergizes the decelerating relay **2P** which thereupon opens its contacts **2P1**, **2P2**, and **2P3**. The opening of the contacts **2P1** re-inserts the resistor **r8** in the circuit of the pattern field of the regulator thus causing the regulator to decrease the amount of power supplied to the generator and thereby decrease the speed of the hoisting motor **H** and the car **C** from intermediate speed to low speed.

As the car approaches still closer to the seventh floor, the counter electromotive force relay **Q** is operated to open its contacts **Q1** in the circuit of the door relay **K** to prepare that relay for operation.

As the car drops still lower and arrives at a point about 7 inches from the seventh floor, it moves the energized inductor relay **L** downwardly to a point where its contacts **2DL** come opposite the top of the inductor plate **F** and are thereby operated to their open position, thus deenergizing the decelerating relay **1P** to decelerate the car to landing speed. The deenergized relay **P** opens its contact members **1P4** in the circuit of the door relay **K** and also opens its contacts **1P1** to reinsert the resistor **r10** in the circuit of the pattern field which reduces the speed of the hoisting motor to what is known as stopping speed (approximately 15 feet per minute).

The deenergized relay **1P** also opens its contacts **1P2** and **1P3** in the circuit of the brake coil **19a** thereby reinserting the resistors **r4** and **r5** in the brake circuit to weaken the brake coil for a quick dropout. It will be noted that the contacts **BK** operated by a mechanical switch (not shown) on the brake still remain open because the brake is still in released condition, thereby rendering effective the operation of the contacts **1P2** and **1P3**.

As the car approaches closely to the floor and the floor of the car comes within, say, one-half inch of the floor level of the landing, the energized inductor relay **L** carries its contacts **1DL** opposite the upper end of the plate **F** and they are thereby operated to their open position, thus deenergizing the down direction leveling relay **LD** which opens its front contacts **LU1** and **LU3** and closes its back contacts **LU2** to stop the car.

The opening of the contacts **LD2** deenergizes the down direction relay **D** which thereupon opens its contacts **D1** and **D2** thus deenergizing

the regulator pattern field circuit and causing the hoisting motor to stop. The opening of the contacts **LD2** also deenergizes the car running relay **M** and the auxiliary car relay **N**. Thereupon the deenergized relay **N** opens its contacts **N2** thus applying the brake **19** to prevent further operation of the hoisting motor and the car.

The car is now stopped level with the floor because the operation of the inductor relay contacts **1DL**, as the car arrived within one-half inch of the floor, caused the shutting off of the power and the application of the brake to stop the car at the instant it leveled with the floor landing.

15 The deenergized relay **N** also recloses its back contacts **N3** and **N4** thereby reenergizing the one-floor run relay **TA** and the smooth start relay **TC** so that they will be ready for use when next needed in the operation of the car.

It should also be noted that the deenergization of the car running relay **M** closes its back contacts **M1** thereby eliminating all of the resistor **r3** from the circuit of the differential field winding **RDF** which gives that field full killing strength for any residual magnetism in the armature **HA** of the hoisting motor. Also the deenergized relay **N** opens its contact members **N1** in the circuit of the generator field winding **GF** to stop the flow of energy through that field winding.

The car has now completed its one-run operation to a stop at the seventh floor.

The foregoing assumed action illustrates how my improved control system operates to cause the car to make a one-floor run in response to an over and back operation of the car switch in which the car attendant merely moves the switch to its "on" position and then immediately returns it to its "center" position for a one-floor run.

Assume now that the car overran its stop or that it drops, due to cable stretch in loading, while it is standing at the seventh floor, say, more than one-half inch below the floor level. This causes the car to be leveled upwardly because when the car moves down the inductor relay contacts **1UL** drop below the lower end of the inductor plate **E** so that they are free from the influence of the plate. Under these conditions the contacts **1UL** reclose and thus energize the up leveling relay **LU** to immediately close its contacts **LU1**, thus energizing the up direction switch **U** to close its contacts **U1** and **U2** in the circuit of the pattern field winding **RPF**, thus preparing it for up operation of the car. The energized switch **U** also closes its contacts **U3** and **U4** thus energizing the car running relay **M** which, in turn, closes its contacts **M4** thus reenergizing the auxiliary car running relay **N**.

60 The energized relay **M** also closes its contacts **M3** thus completing the energization of the pattern field winding **RPF** of the regulator to cause the starting of the hoisting motor for moving the car in the up direction. The energized relay **N** closes its contacts **N2** thus completing the circuit through the brake coil **19a** and causing the brake **19** to be released so that the car may be returned to its position level with the floor landing. The energized relay **N** also opens its contacts **N3** and **N4** in the circuit of the one-floor run relay **TA** and the smooth start relay **TC** thus preparing them for eventual operation after their time delay expires.

65 As the car moves upward in returning to its po-

sition level with the seventh floor landing, it carries the inductor relay L to the position where its contacts 1UL come opposite the lower end of the plate E and are again opened thus de-energizing the leveling relay LU which, in turn, opens its contacts LU1 thus deenergizing the up direction switch U, the car running relay M and the auxiliary car running relay N. The deenergized relay M opens its contacts M3 thus deenergizing the pattern field winding RPF and opens its contacts M2 thus deenergizing the brake coil 19a and returning the brake to its applied position to hold the car level with the seventh floor.

The deenergized relay N recloses its back contacts N3 and N4 to reenergize the one-floor run relay TB and the smooth start relay TC ready for the next operation of the car.

The foregoing action illustrates how the releveling operation takes place when the car, for any reason, moves below the floor level of the landing at which it is stopped. If the car should drift away from the floor in the up direction for any reason, the contacts 1DL on the inductor relay L would be moved above the upper end of the inductor plate F and thereby cause energization of the down leveling relay LD to return the car to its floor level.

It will be assumed now that the attendant on the car again moves the car switch to its down running position and leaves it there for a down run from the seventh floor to the fourth floor. This is more than a one-floor run and, therefore, the operation of the one-floor run relay TA when it times out will have no effect on the system. The movement of the car switch for the down floor run engages the contact 33 thus energizing the down direction relay DR as previously described. The energized relay DR closes its contacts DR5 thus energizing the antiplugging relay TB, opens its contacts TB3 thereby deenergizing the inductor relay L which causes the closing of its contacts 1UL, 1DL, 2UL, 2DL and they, in turn, energize the up leveling relay LU, the down leveling relay LD, the low speed decelerating relay 1P and the intermediate speed decelerating relay 2P, as previously described in connection with the one-floor run operation.

The energized relay DR also closes its contacts DR6 thus energizing the door relay K to effect the closing of the car gate and the floor door (not shown) thus closing the gate and door safety contacts 40 and 41 thus energizing the down direction switch D which, in turn, energizes the high speed decelerating relay 3P and the car running relay M. The car running relay M energizes the auxiliary car running relay N which, in turn, deenergizes the time delay relays TC and TA and also energizes the brake coil 19a to release the brake 19, all as previously described in connection with the one-floor run.

The timing relay TC now times out after the expiration of .3 of a second and energizes the high speed start relay GR which closes its contacts GR1 thus short circuiting the resistors r7, r8, r9 and r10 in the pattern field circuit of the regulator, which causes the car to run at its normal high speed as previously described. The deenergized relay TC also opens its contacts TC1 thus partially preparing the pattern field circuit for use when the car is to be decelerated.

It will be recalled that the car attendant in making this more than one floor run to the fourth floor keeps the car switch in its closed position. Therefore, the opening of the contacts TA1 in the holding circuit provided by those contacts

for the down direction relay DR has no effect on that relay.

After the expiration of 1.8 seconds from the time the car was started, the one-floor run relay TA times out and opens its contacts TA1, but this has no effect on the operation of the car because the car switch remains closed on its contact 33 which keeps the down direction relay DR energized.

When the car arrives at a position where it is from one-half to one floor above the fourth floor at which it is to be stopped, the attendant centers the car switch CS to cause the car to stop at the fourth floor. The centering of the car switch CS removes it from the contact 33 thus deenergizing the down direction relay DR which closes its back contacts DR1 and DR3 and opens its front contacts DR2, DR4, DR5 and DR6. The opening of the contacts DR4 deenergizes the high speed start relay GR which opens its contacts GR1 in its short circuit around the resistors in the pattern field circuit. Inasmuch as the decelerating relays 3P, 2P and 1P are in energized condition, the resistors r8, r9 and r10 still remain short circuited but the resistors r6 and r7 remain in the circuit of the field RPF. This condition reduces the supply of energy to the pattern field circuit and thus causes a reduction in the high running speed of the hoisting field motor and the car and prepares the car to be decelerated to the stop at the fourth floor.

The deenergization of the relay DR by opening its contacts DR5 also deenergized the anit-plugging relay TB which at the end of .3 second closes its back contacts TB3 and thereby energizes the inductor relay L to effect deceleration of the car as it makes its down approach to the inductor plate E for the fourth floor. The operation of the inductor relay, its contacts and the decelerating relays controlled thereby will follow exactly as previously described in connection with the stopping of the car at the seventh floor while making its one-floor run. Hence no further description of the deceleration of the car will be given.

This assumed operation illustrates how the system acts in making a more than one-floor run.

This control system is designed to give a quick leveling action without releveling in about 70% of the operations. All motoring loads will come to the floor quickly and without pause or overrun. Overhauling loads from nearly empty car up to approximately 70% load down will come in likewise. Empty car up and 80% load down will usually overshoot the floor about one-half inch and relevel quickly. Full load down will overshoot the floor about three inches and relevel, provided in each case that the starting switch is centered in time to permit retardation to high leveling speed before entering the leveling zone.

The action of coming into the floor quickly is obtained by making the high leveling speed (3P closed) and the retardation after entering the leveling zone (the inductor plate zone) just sufficient to cause the car to stop level with the floor. The speeds to which the car is decelerated by the closing of the relays 1P or 2P should be sufficient that, if the car overtravels the floor 7 inches or 14 inches or more, it will return at a speed sufficient to prevent a pause coming to the floor and to prevent overtravel of the floor. With these settings the car will never come short of the floor but will stop level or run past it. The operation of returning to the floor has been observed to

be much faster than stopping short (pausing) and then continuing to the floor.

The system is particularly suited to an elevator with a car having a high running speed of approximately 350 feet per minute, and in which the retention of the resistors r_6 and r_1 in the pattern circuit by the opening of contacts GR_1 will reduce the high-running speed of the car to a high decelerating speed of approximately 200 feet per minute as it moves the inductor relay down to the inductor plate zone. Then as the car enters the inductor plate zone, the high speed decelerating relay $3P$, the intermediate speed relay $2P$, and the low speed relay $1P$ are deenergized in quick succession. This rapid weakening of the regulator pattern field combined with the strengthening of the differential field produces a rapid retardation which tests show will stop any car load except the heaviest loads level with the floor without overrun, underrun in any zone of approach at a regulated constant speed. It is believed that this action is produced through the slightly unstable characteristic of the regulator due to its abnormally strengthened differential field acting to produce a proportionately stronger retardation for a loaded car than for a balanced car.

In operating this system, some variation in operation has been found traceable to changes in temperature. When the motor gets considerably hotter than would be expected in normal operation, the car will overtravel approximately an inch and then return, where a cooler motor would cause a level stop without overtravel. It is anticipated that cold conditions, such as may occur in some penthouses in the winter, will cause the car to stop short of every stop while the temperature remains low.

I have provided a remedy for this by including a resistor in circuit with one of the field windings of the regulator and means for short-circuiting that resistor to suit the weather conditions. The resistor may be included in either the pattern field winding circuit or in the loop circuit 22 connecting the self-exciting field winding RCF and the generator field winding GF . In this instance I have included a resistor r_1 in the loop circuit 22 and have provided for its control by means of a push button 31 which may be located in the elevator car C for operation by the car attendant. I have also provided a thermostat 34 which may be mounted on the frame of the regulator and connected to so control the resistor r_1 in accordance with temperature conditions as to secure the same degree of operation under various conditions of temperature. The thermostat may be adjusted to short out a few ohms of resistance to correct for the change in temperature when the frame heats up a predetermined amount. In tests, it has been found that three ohms are about the correct amount to short out. Normally, I supply around eight ohms cold for the adjustment of the loop when the apparatus is installed and placed in operation.

The circuits for the system illustrated and described have purposely been shown in the simplest manner, omitting for simplicity the motor field control, the discharge rectoxes around the leveling switch coils and other places, and the safety circuit and door operating circuits, as they may be readily supplied by any one skilled in the art. The time relays are indicated merely by discharge resistances.

Although I have illustrated and described only one specific embodiment of my invention, it is

to be understood that modifications thereof and changes therein may be made without departing from the spirit and scope of the invention.

I claim as my invention:

1. In a control system for an elevator car serving a plurality of landing floors, a power generator provided with an armature and a field winding, a hoisting motor connected in a loop circuit with and controlled by said armature for operating the car; a regulator for energizing and controlling the field winding of the power generator, said regulator having field windings including a differential field winding; a switch, a control device, means responsive to a temporary operation of the switch for operating the control device, means responsive to operation of the control device for starting and running the car, means for controlling the regulator to decelerate the hoisting motor, a timing device for maintaining the control device in its operated condition for a predetermined time after it is operated and then causing it to be restored to its unoperated condition, means responsive to the return of the control device to its unoperated condition for rendering the decelerating means effective to cause the hoisting motor to decelerate the car as it approaches the next floor, and means responsive to operation of the decelerating means for strengthening the differential field to render the deceleration more effective.

2. In a control system for an elevator car serving a plurality of landing floors; a power generator provided with an armature and a field winding, a hoisting motor connected in a loop circuit with and controlled by said armature for operating the car; a regulator for energizing and controlling the field winding of the power generator, said regulator including a differential field winding; a switch, a control device, means responsive to a temporary operation of the switch for operating the control device, means responsive to operation of the control device for starting and running the car, means for controlling the regulator to decelerate the hoisting motor, a timing device for maintaining the control device in its operated condition for a predetermined period of time after it is operated and then causing it to be restored to its unoperated condition, means responsive to restoration of the control device to its unoperated condition for rendering the decelerating means effective to cause the hoisting motor to decelerate the car as it approaches the next floor, means responsive to operation of the decelerating means for strengthening the differential field of the regulator to render the deceleration more effective, a leveling means for controlling the motor to relevel the car, and a time delay means responsive to the restoration of the control device to its unoperated condition for preventing the leveling means from reversing the connections of the regulator for a predetermined time.

3. In an elevator system for operating a car serving a plurality of landing floors, a switch, a car starting and running means, a control device responsive to a temporary operation of the switch for operating the car starting and running means, means for causing the car to decelerate and stop at a floor, and a time delay device responsive to operation of the car starting and running means for maintaining the control device in operation for a predetermined period of time after it is operated and for then rendering

the decelerating and stopping means effective to decelerate and stop the car for the next floor.

4. In a motor control system for an elevator car, means for starting and operating the car including a car switch and a stopping means; means responsive to a temporary operation of said switch for causing the car to accelerate from a low speed to a high speed; a timing mechanism responsive to the starting of the car for initiating a time period; means responsive to said time mechanism for maintaining the accelerating means in operation for a predetermined time period and at the end of said time period for rendering said accelerating means ineffective so that the car retards in speed; means responsive to the approach of the car to a floor for actuating said stopping means; whereby the car will, in response to a temporary actuation of said car switch, start, accelerate to a high speed, retard to a low speed, and stop accurately at a floor adjacent to the one from which the car started.

5. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; control means for connecting the pattern field winding to a source of energy to operate the motor at its high running speed, decelerating means for controlling the regulator to decelerate the motor, and means responsive to operation of the decelerating means for strengthening the differential field of the regulator to render the deceleration more effective.

6. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; control means for connecting the pattern field winding to a source of energy to operate the motor at its high running speed, decelerating means for controlling the regulator to decelerate the motor, and means responsive to operation of the decelerating means for weakening the pattern field winding in rapid successive steps and strengthening the differential field winding to produce a rapid retardation of the motor.

7. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; decelerating means for controlling the regulator to decelerate the motor, a resistor disposed in series with the differential field winding, and means responsive to operation of the decelerating means for short-circuiting a portion of the resistor to strengthen the differential field to render the deceleration more effective.

8. A variable voltage system of control comprising a power generator provided with an

armature and a field winding and a motor connected in a loop circuit with said armature; a regulating generator for energizing the field winding of the power generator, said regulating generator having an armature, a series field winding, a differential field winding, a self-exciting field winding, and a pattern field winding; decelerating means for controlling the regulator to decelerate the motor, a resistor disposed in series with the differential field winding, means responsive to operation of the decelerating means for short-circuiting a portion of the resistor to strengthen the differential field to render the deceleration more effective, a resistor disposed in series with the series field winding, and means responsive to operation of the decelerating means for short-circuiting a portion of the resistor in the series field winding for strengthening the series field to keep the regulator regulation flat.

9. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; decelerating means for controlling the regulator to decelerate the motor, a resistor disposed in series with the differential field winding, means responsive to operation of the decelerating means for short-circuiting a portion of the resistor to strengthen the differential field to render the deceleration more effective, means for controlling the regulator to stop the motor, and means responsive to operation of the stopping means for short-circuiting an additional portion of the resistor to strengthen the differential field still further for field killing purposes.

10. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; decelerating means for controlling the regulator to decelerate the motor, and means responsive to operation of the decelerating means for strengthening the differential field of the regulator to render the deceleration more effective and for strengthening the series field when the car is in the decelerating zone for keeping the regulator regulation flat.

11. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; decelerating means for controlling the regulator to decelerate the motor, means responsive to operation of the decelerating means for strengthening the differential field of the regulator to render the deceleration more effective and for strengthening the series field when the car is in the decelerating zone for keeping the regulator regulation flat, means for stopping the motor,

and means responsive to operation of the stopping means for further strengthening the differential field for field killing purposes.

12. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; control means for connecting the pattern field winding to a source of energy to operate the motor at its high running speed, decelerating means for controlling the regulator to decelerate the motor, means responsive to operation of the decelerating means for strengthening the differential field of the regulator to render the deceleration more effective, and means for decreasing the resistance in a field winding of the regulator for compensating for a low temperature condition of the apparatus.

13. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding;

control means for connecting the pattern field winding to a source of energy to operate the motor at its high running speed, decelerating means for controlling the regulator to decelerate the motor, means responsive to operation of the decelerating means for strengthening the differential field of the regulator to render the deceleration more effective, and a thermostat associated with the regulator for decreasing the resistance in a field winding circuit for compensating for a low temperature condition of the apparatus.

14. A variable voltage system of control comprising a power generator provided with an armature and a field winding and a motor connected in a loop circuit with said armature; a regulating generator for energizing the field winding of the power generator, said regulating generator having an armature, a series field winding, a differential field winding, a self-exciting field winding, and a pattern field winding; control means for connecting the pattern field winding to a source of energy to operate the motor at its high running speed, decelerating means for controlling the regulator to decelerate the motor, means responsive to operation of the decelerating means for strengthening the differential field of the regulator to render the deceleration more effective, and a manually operated switch for decreasing the resistance in a field winding circuit of the regulator to compensate for a low temperature condition of the apparatus.

WILLIAM F. EAMES.
